UNITED STATES PATENT OFFICE.

VERNON HOXIE, OF ADRIAN, MICHIGAN.

STAPLE FORMING AND DISCHARGING MECHANISM.

948,699.

Specification of Letters Patent.

Patented Feb. 8, 1910.

Application filed February 15, 1909. Serial No. 477,932.

To all whom it may concern:

Be it known that I, VERNON HOXIE, a citizen of the United States, and a resident of Adrian, in the county of Lenawee and State 5 of Michigan, have invented a certain new and useful Staple Forming and Discharging Mechanism; and I do hereby declare the following to be a full, clear, and exact description of the invention, such as will 10 enable others skilled in the art to which it appertains to make and use the same, reference being had to the accompanying drawings, and to the figures and letters of reference marked thereon, which form a part of 15 this specification.

My invention relates to wire working machinery, and particularly to means for use in conjunction with wire-fence machines or the like for successively forming staples 20 from sections of wire fed thereto, discharging such staples from such means and clamping them about the intersecting portions of a fabric being woven.

The object of my invention is the provision 25 of mechanism of this class, which is simple and efficient in its operation and so constructed as to occupy a very narrow space in the machine, thus adapting a plurality of the same to be used in connection with the 30 manufacture of chicken fabric or the like in which the warp wires or a portion of them are disposed closely together.

Further objects of the invention, as well 35 as the operation, construction and arrangement of the parts thereof, are fully described in the following specification, and two forms of the same are illustrated in the accompanying drawings, in which,—

Figure 1 is a side elevation of a portion 40 of a machine equipped with my invention and illustrating an associated operating mechanism. Figs. 2 and 3 are reverse side elevations of the mechanism comprising my invention, with the staple forming and 45 driving parts retracted. Fig. 4 is a plan of the same together with the staple cylinder actuating mechanism. Fig. 5 is a side view of the staple-discharging plunger and its attached bar. Fig. 6 is a rear end view of 50 the staple-cylinder. Fig. 7 is a similar view thereof with the actuating ratchet-arm and attached operating bar associated therewith. Fig. 8 is a plan of the circumferential portion of the cylinder actuating cam as it 55 would appear unrolled or flattened out. Fig.

9 is a side elevation of a slightly modified form of my invention. Figs. 10 and 11 are sections on the line $x-x$ in Fig. 9, the former with the staple-forming gate raised to forming position, and the latter with the 60 gate lowered to staple-discharging position. Fig. 12 is an enlarged side elevation of such gate. Fig. 13 is a cross-section of the gate on the line $y-y$ in Fig. 12, and Fig. 14 is an unrolled plan of the cam employed to 65 operate the gate-bar to raise and lower the gates.

My invention in its broader aspect may be embodied in different forms of mechanisms and in the present instance I have 70 shown and described two forms, a preferred form, which is illustrated in Figs. 2 to 8 of the drawings, and a modified form, which is illustrated in Figs. 9 to 14.

Referring to the preferred form of my 75 invention, 1 designates the holder thereof, which has its upper surface preferably inclined, as shown, and vertically grooved or recessed from its rear end forwardly, as at 2, Figs. 2 and 4, to receive the plunger 3. 80 This plunger is shown as being provided in its sides with longitudinal grooves 4 for receiving complementary guide ribs 5 formed on the walls of the holder groove 2, and is provided at its forward end with the staple- 85 discharge nose 6, which works into a staple-discharge way or shallow extension 7 of the groove 2.

Mounted at the forward end of the holder 90 immediately above the staple-discharge way 7 therein is a staple cylinder or rotary staple magazine 8, which is disposed longitudinally of said discharge way and has end trunnions journaled in bearings 9, 9 rising from the holder top. This cylinder is provided 95 with a plurality of longitudinally extending circumferential grooves 10, in the present case four in number, the side walls of which are concaved or half rounded to adapt each to hold a staple drawn therein. When 100 the cylinder is turned these grooves successively move into register with the staple-discharge way 7.

The wire thread from which the staples are formed is shown at α in Fig. 3, and feeds 105 upwardly through a cutaway portion 11 in one side of the holder 1 at the forward end thereof and an opening 12 in a cutter bar or plate 13 and thence through an opening or cutaway portion 14 in advance of a groove 110

10 in the side of the cylinder 8 which is contiguous to the plate 13. This cutter-bar or plate is carried by the holder 1 for reciprocatory movements in a plane parallel to the 5 axis of the cylinder 8 and is normally held at its limit of forward movement by the action thereon of a contraction spring 15, which attaches at its forward end to the rear end of the holder 1 and at its rear end 10 to a pin or screw 16 projecting from the rear end of the cutter-bar. As the cutter-bar moves rearwardly from its limit of forward movement the section of wire previously fed to the opening or cutaway portion 14 of the holder is severed from its thread due to the 15 opposed shearing action of the upper end of the wall of the opening 12 and the fixed cutter part 17 at the lower end of the opening 14, see Fig. 3. As the section is severed 20 from its thread it is engaged midway between its ends by a stud 18 projecting inwardly from the cutter-bar 13 and drawn thereby within a registering groove 10 in the contiguous side of the cylinder 8 and 25 formed into a staple b. The cutter-bar 13 is caused to move rearwardly with the plunger 3 during the last portion of the rearward movement of such plunger due to a stud or pin 19 projecting from a boss 20, 30 rising from said plunger, and working in a slot 21 in the plate, as shown.

A ratchet-lever 22 is loosely mounted on the rear trunnion of the cylinder 8 with its toothed surface held in yielding contact 35 with the contiguous toothed end of the cylinder, due to the action of the coiled compression spring 23 thereon, thus causing this lever, when oscillated in the direction of engagement of such teeth, to move the cylinder therewith, and when oscillated in the opposite direction to have movement relative to the cylinder.

The lever 22 has properly timed oscillations imparted thereto to intermittently impart a quarter turn to the cylinder 8, should it be provided with four grooves 10, and then to return to its starting position, by the reciprocatory movement of an operating-bar 24, which has slotted connection 40 with the outer end of the lever 22, as shown at 25, Fig. 7, and also with the outer end of the lever of each of the other staple forming and discharging devices associated with the loom, whereby movements are imparted in 45 unison to the cylinders of the several devices. The bar 24 works through a guide 26 at one side of the machine frame 27, see Fig. 4, and has reciprocatory movements imparted thereto due to a roller 28 which 50 is carried at its under side near one end working in a cam-groove 29 formed circumferentially in a drum or roll 30. This drum or roll has its shaft ends mounted in bearings 31, 31 rising from one side of the machine frame 27, and mounted on the shaft 55

therewith is a ratchet-pinion 32, which, when rotated in one direction, is adapted to rotate the drum therewith and when rotated in the other direction to turn freely relative to the drum. The pinion 32 meshes 70 with and has a complete rotation imparted thereto in each direction of movement of a rack-bar 33, which has reciprocation imparted thereto as hereinafter described.

The cam-groove 29 is so formed that the 75 roller 28 will travel in a neutral zone c thereof (Fig. 8) during the first portion of the forward stroke of the plunger 3 and cutter-bar 13, or until such bar has moved forward sufficiently to move the staple forming stud 18 thereof free from the registering groove 10 of the cylinder. When the cylinder is thus free to turn, the roller 28 enters the cam portion d of the groove 29, which effects a movement of the bar 24 to 80 throw the lever 22 attached thereto in the proper direction to rotate the cylinder 8 to move a staple-filled groove thereof into the path of movement of the discharge nose 6 of the plunger. During the remainder of the 85 rotation of the cam-roll the roller 28 travels back to the neutral portion c of the cam groove through the cam portion e thereof, thus returning the bar 24 and lever 22 to their normal or starting positions. During 90 this return movement of the bar 24 and lever 22 the plunger is acting on the registering 95 staple to discharge it from the cylinder 8 and holder 1 and to clamp it about the alining parts of the fabric being woven.

In Fig. 1 is illustrated a simple mechanism for intermittently feeding lengths of wire to the staple former and operating the plunger 3 and rack-bar 33, which mechanism is similar to that disclosed in my former 105 United States Letters Patent No. 879,965. In this figure 34 may designate a drive-shaft, which carries a gear 35 for meshing with the two opposing gears 36 and 37. On the former shaft is mounted a semi-gear 38, which meshes with a semi-piston 39 on the shaft 40, and through it communicates rotation to the gear 41, which drives the small gear 42 through the medium of the idler-gear 43. The gear 42 is carried by one of a 110 pair of feed-rolls 44 between which the wire a passes and is frictionally gripped to cause it to be fed to the forming apparatus when said rolls are rotated, thus causing a properly timed intermittent movement to be communicated to said wire from a continuous rotation of the gear 35. Mounted on the shaft with the gear 36 is an eccentric 45 carrying an eccentric rod 46, which connects with toggles 47 and through them imparts 115 reciprocatory movements to a table 48, which is mounted for movement on a portion of the machine frame 27 and in turn connects with the plungers 3 of the several staple-forming and discharging devices of the ma- 120

chine through the medium of links 49 and imparts the requisite reciprocations in unison thereto, and also imparts rotation to the rack-bar 33. In the operation of this form 5 of my invention a length of wire is fed to the holder 1 while the cutter-bar or plate 13 is at the limit of its forward movement, or during the period of relative movements of such bar and the plunger 3, which is permitted 10 by reason of the pin 19 carried by the plunger working in the slot 21 in said bar. When the plunger 3 has receded to within a short distance of its limit of rearward movement the pin 19 carried thereby moves into 15 contact with the rear end of the slot 21 in the cutter bar 13 and causes the said bar to move the remainder of such rearward throw therewith against the tension of the spring 16, thus causing the fed length of the wire 20 to be severed by the shearing action of the apertured face of the bar 13 and cutter-part 17, and causing the stud 18 on such bar to act on the severed section to draw it within a registering groove 10 in the cylinder 8 and 25 form it into a U-shape, as shown in Fig. 3. On the reverse or forward movement of the plunger 3, the cutter-bar 13 moves forward therewith the full length of its forward throw under the influence of the spring 16; 30 and as soon as the staple forming stud 18 thereon has moved out of the registering grooves 10 of the cylinder 8, and prior to the entrance of the staple-discharging nose 6 of the plunger into a registering groove of such 35 cylinder, the roller 28 on the bar 24 enters and passes through the portion *d* of the groove 29 in the roll 30 and moves such bar to throw the levers 22 to which it is attached so as to impart a sufficient movement to the 40 associated staple-carrying cylinders 8 to move the next staple-carrying groove thereof in register with the advancing discharge nose 6 of the plunger, and at the same time moving an empty groove 10 into register 45 with the staple forming stud 18 to permit a staple to be drawn therein on the next rearward movement of the cutter-bar 13. On the continued forward movement of the plunger the discharge-nose 6 thereof enters 50 the staple filled groove which is in register therewith and effects an ejection of the staple therefrom and clamps it about the alining portions of the fabric being woven, and at the same time the roller 28 on the bar 55 24 traverses the length of the portion *c* of the cam-groove 29, thus returning the bar 24 and lever 22 to their normal positions. A length of the wire *a* is fed to the holder while the cutter-bar 13 is at rest by the 60 properly timed action of the wire-feeding mechanism.

It is thus apparent that I have provided a staple forming and discharging mechanism which is of compact form, thus enabling a 65 plurality of the same to be placed side by

side in a very small space to adapt them to be used in connection with machines for weaving fabrics, the warp wires of which are closely positioned, and one which is simple and efficient in its construction and operation. It is also evident that a grooved portion of the staple cylinder is always visible intermediate the staple receiving and discharging points thereof, thus enabling the operator to note a miss in the forming of a 70 staple in time to stop his machine and press a formed staple into the empty groove by hand, so that no imperfections will occur in the fabric.

The modified form of my invention, which 80 is shown in Figs. 9 to 14, is the same in construction and operation as the form above described, except that an oscillatory staple-forming gate is employed in place of the cylinder 8. In this construction A is the 85 holder; B the link connecting the plunger to the table 48; C the plunger; D the cutter bar having the staple-forming stud E thereon; F the staple receiving gate, which is pivoted to the holder as at *f*; G an arm fixedly 90 projecting therefrom, and H the cam-actuated gate-operating bar, which attaches to the arm C of the gate. The gate F is provided on the under side thereof, when in horizontal position, with a longitudinally 95 extending groove *g* into which the wire sections is drawn and formed into U-shape when the gate is in vertical position, as shown in Figs. 9, 10 and 12, by the action of the stud E on such section, and from which 100 the staple is discharged when the gate is in reclining or horizontal position, as shown in Fig. 11. When the gate is up the stud E works through a slot *h* therein and projects outwardly through the groove *g* a sufficient 105 distance to engage and draw a section of wire therein when the cutter-bar is moved rearwardly. With this construction the cam-groove in the roller actuating the movements of the bar 4 describes a course substantially like that shown in Fig. 14. With 110 this form of cam-groove, the bar H is moved to throw the gate into staple-discharging position during the first portion of the forward movement of the plunger by reason of 115 the roller (not shown) on said bar traveling through the cam portion *i* of the cam-groove. The roller then enters a neutral portion *j* of the groove and travels therein during the period of discharge of the staple from the 120 gate, after which the gate is raised to staple-receiving position by the roller traveling through the cam portion *k* of the groove. As the roller leaves the portion *k* of the groove it enters and travels in the neutral 125 portion *l* thereof during the remainder of the rearward stroke of the plunger, or while a wire section is being drawn into the gate groove to form it into U-shape.

I wish it understood that my invention is 130

not limited to any specific construction or arrangement of parts except in so far as such limitations are specified in the claims.

Having thus described my invention, what I claim as new and desire to secure by Letters Patent, is,—

1. In an apparatus of the class described, the combination of a holder, a part intermittently movable to receive a staple in one position and have it discharged therefrom in another position, means for moving said part for such purposes, a plunger slidingly carried by said holder and movable to eject a staple from said part, and a member carried by said holder and movable by said plunger for a portion only of its stroke, and adapted to draw a wire section into said part to form a staple therein.

2. In an apparatus of the class described, the combination of a holder having a suitable discharge-way in its upper portion, a rotatable member carried by the holder contiguous to the side of such discharge-way and intermediate its ends, said member being adapted to move staples from forming position to discharging position, and mechanism operative to coöperate with said member to form staples therein in one position of its movements and to discharge the same therefrom at another position in its movement, and means for intermittently rotating such member.

3. In an apparatus of the class described, the combination of a holder having a staple discharge-way therein, staple forming and discharging parts carried by such holder, a pivotally movable member carried by such holder adjacent one side of said way with its axis parallel thereto and adapted to move staples from forming to discharging position, and to coöperate with the forming part to form staples, means controlling the movements of said forming and discharging parts, and means controlling the movements of said member.

4. In an apparatus of the class described, the combination of a holder, a cylinder carried by said holder and having staple-receiving sockets provided therein, a ratchet-arm in yielding engagement with an end of said cylinder and adapted when oscillated to impart intermittent rotation to the cylinder, cam means controlling the movements of said arm, means for feeding lengths of wire to said holder, means carried by said holder and movable to sever such lengths and to draw the same into the cylinder to form staples, means for ejecting the staples from the cylinder when moved by the cylinder to a different position from that in which they were formed, and mechanism for imparting operative movements to said cam mechanism and said staple-forming and ejecting means.

5. In an apparatus of the class described,

a holder, a plate mounted on the side of such holder for reciprocatory movements, said plate having a staple forming projection on its inner face, a plunger reciprocally carried by said holder and coacting with said plate to impart movements thereto during a portion of the movements of such plunger, a pivotally movable staple carrying member mounted on such holder with its axis disposed in a plane parallel to the plane of movement of such plunger, said member being adapted to coöperate with the projection on such plate to form a staple therein and means for moving said member on its pivot to move the staples carried thereby from forming to discharging position.

6. In an apparatus of the class described, a holder having its top grooved to form a guide-way longitudinally thereof, a staple discharging plunger movable in said guide-way, a staple carrying member pivotally carried by the holder adjacent to such guide-way and having its axis disposed in parallelism therewith, said member being adapted to coöperate with a male staple forming part to form a staple and to move the formed staple from forming to discharging position, means for moving such member, and means intermittently movable to coöperate with said member to form a staple therein.

7. In an apparatus of the class described, a holder having a staple discharge-way therein, a staple discharging plunger movable in said way, a male staple forming part carried by said holder and reciprocally movable in one direction by the plunger, a pivotally movable member for moving staples from forming to discharging position and which coöperates with said male staple forming part to form staples, said member being disposed adjacent to such guide-way and having its axis parallel thereto, and means controlling the movements of said member.

8. In an apparatus of the class described, the combination of a holder having a staple discharge-way therein, a pivotally movable staple carrying member mounted at one side of said way with its axis parallel thereto, and adapted to move staples from forming to discharging position, means for coöperating with said member to form staples therein, means movable in said way to discharge the formed staples from such member, and means for intermittently moving said member.

9. In an apparatus of the class described, the combination of a holder having a staple discharge-way therein, a pivotally movable member mounted adjacent to one side of such discharge-way with its axis parallel thereto, and having a plurality of peripheral longitudinally extending grooves adapted to be moved into register with said discharge-way as the member is rotated, means for in-

termittently rotating said member, and mechanism having a part movable to co-operate with said member to intermittently form staples in the grooves thereof and a 5 staple discharge part which operates in said way and through the registering grooves of said member.

10 10. In an apparatus of the class described, the combination of a holder having an inclined discharge-way therein, a member rotatably mounted adjacent to such way with its axis parallel thereto and adapted to move staples from forming to discharging position, means carried by the holder and movable to co-operate with said member to form staples therein, a plunger movable in said way and adapted to discharge staples from said member, and means for rotating such member.

15 20 11. In an apparatus of the class described, a holder, a rotary staple magazine mounted on the top of such holder, a part carried by

25 said holder at the side of said magazine and movable to co-operate with said magazine to form wire sections into staples, said part having a longitudinal slot therein, a staple discharging plunger reciprocally movable beneath the said magazine to discharge the formed staples therefrom and having a part 30 operating in said slot whereby a staple forming movement is imparted to said part from the plunger, means yieldingly acting on said part to normally retain it in one position, means for controlling the movements of said magazine, and means for reciprocating the 35 plunger.

In testimony whereof I have hereunto signed my name to this specification in the presence of two subscribing witnesses.

VERNON HOXIE.
